[57] CLAIM

The ornamental design for a comb-shaped holder for a hair cutting razor, as shown and described.

DESCRIPTION

FIG. 1 is a front elevational view of a comb-shaped holder for a hair cutting razor showing my new design; FIG. 2 is a rear elevational view; FIG. 3 is a right side elevational view; FIG. 4 is a left side elevational view; FIG. 5 is a top plan view; and FIG. 6 is a bottom plan view thereof. FIG. 7 is a perspective view of the holder in open position.
